UNITED STATES PATENT OFFICE

2,156,825

CONVERTIBLE DRESSER

Olav Thorsen, Brooklyn, N. Y.

Application May 14, 1938, Serial No. 207,950

1 Claim. (Cl. 5—2)

This invention relates to convertible articles of furniture and pertains more particularly to a combination dresser and bed; and the principal purpose of the invention is to provide a compact, neat and efficient convertible article of furniture which has the appearance and utility of a dresser during the day time, and which is provided with a folding spring and mattress so that it will serve as a comfortable, three-quarter width bed during the night time or at other times when the spring and mattress are unfolded.

Further objects of the invention reside in the novel features of construction of the convertible dresser hereinafter described and illustrated in the accompanying drawings, particularly the provision of hinged sections which serve alternatively as the front and top of the dresser or as the frame or support for the spring and mattress.

In the drawings,

Fig. 1 is a front elevation of the improved structure, showing the bed folded into the body of the article of furniture for use as a dresser;

Fig. 2 is a side elevation looking to the right of Fig. 1;

Fig. 3 is a plan view of the convertible dresser; Fig. 4 is a vertical section on line 4—4 of Fig. 1;

Fig. 5 is a plan view, showing the spring and mattress unfolded for use as a bed; and

Fig. 6 is a side elevation of Fig. 5, with portions of the construction broken away.

In the form chosen for the purpose of illustration, the convertible dresser is constructed of wood or other suitable material and comprises side members 11, a back member 12, a base 13, and a horizontal partition 14 suitably connected to the side and back members and defining upper and lower compartments of the article. A drawer 15 is received in the lower compartment between the base 13 and the partition 14, and the front 16 of the drawer constitutes the front of the lower compartment. The sides 11 and back 12 extend upwardly a substantial distance, the back projecting at 17 above the sides, and having a ledge or shoulder 18 spaced a short distance below the upper ends of said sides.

A front section 19 for the upper compartment is hinged at 20 to the partition 14; and a top section 21 is hinged at 22 to the upper or outer end of the front section 19. Sections 19 and 21 constitute the front and top of the closed dresser, and also (together with partition 14) form the frame or support for the folding spring 23 and mattress 24 when the dresser is converted into a bed as shown in Figs. 5 and 6.

When folded to the closed position shown in

Figs. 1 to 4, the front section 19 has the appearance of the front of a drawer and may be provided with handles similar to those on the drawer front 16; and the flat top section 21 is similar in appearance to an ordinary dresser top. The end of the top section 21 rests upon and is supported by the ledge 18, between the extreme upper ends of the sides 11 and against the projection 17 of the back 12, so that the edges of the top section are substantially concealed from view, the exposed surface of said section being flush with the upper ends of the dresser sides 11 to avoid objectionable obstructions on the dresser top.

The upper compartment is sufficiently large to contain the folding spring 23 and mattress 24 which are folded endwise upon each other, as illustrated in Fig. 4. As thus shown, the spring comprises three box spring sections, hinged together, but it will be understood that any other suitable type of folding spring may be employed for this purpose.

When converted into a bed, the front and top sections 19 and 21 swing forwardly of the dresser and are supported flatwise, in line with partition 14, by legs 25 attached to the free end of section 21 by hinges 26 in such a manner that the legs may be folded inwardly onto the top section 21 when the latter is in the position shown in Figs. 1 to 4. If additional support is desired for the central portion of the frame of the open bed, the dresser drawer 15 may be pulled out so that its front 16 is located just below and against the central portion of section 19, as indicated by the broken lines in Fig. 6.

When the bed is folded into the dresser with the upper compartment closed, it will be observed that the legs 25 swing inwardly so that their ends approximately meet at the center of the dresser top, and that the rearward sides of the legs fit against the upper end 17 of the back wall 12, and are concealed thereby. Hence, the folded legs are inconspicuous and appear to be a part of the closed dresser; and it will be apparent that the visible portions of the hinges 26 may be covered by ornamental fabrics or articles which usually decorate a dresser top. The closed dresser thus presents a neat and attractive appearance, and may be used in a bedroom without detracting from the ornamental aspects of other articles of furniture; it is compact in size and relatively light in weight, so that it may readily be moved from place to place; and the drawer 15 is of ample size to hold bedding material, clothing, and other articles. When opened, the bed occupies a minimum of additional space, inasmuch as a

large portion of it rests upon the permanent partition 14, between the side walls of the dresser; yet the bed is of ample size and the spring and mattress afford adequate comfort to the occupant or occupants, and also permit of easy and convenient bedmaking. The article is of simple and economical construction and may be quickly and easily converted from a bed to a dresser, and vice versa, with a minimum of effort.

10 It will be understood that the structural details herein disclosed may be varied to suit particular purposes without departing from the essence of this invention as defined in the following claim.

15 I claim:

A convertible dresser of the class described, comprising side and back members, a horizontal partition connecting the side members and providing upper and lower compartments, a drawer disposed in the lower compartment, a front section for the upper compartment, hinged to said

partition and adapted to be swung outwardly to a position in the plane of the partition, a top section hinged to said front section and adapted to be swung inwardly to form a closed upper compartment for holding a folded spring and mattress, and outwardly to a position in the plane of the partition and top section, thereby to serve as a bed frame, the back member projecting upwardly above the side members and having a ledge disposed below the tops of the side members for supporting the top section flatwise on top of the dresser and between said side members, and legs hinged to the corners of the top section for supporting the same in the plane of said partition when the sections are swung outwardly to bed-supporting position, the legs being foldable inwardly onto the exposed surface of the top section and against the upwardly projecting back member when the sections are in closed position.
